DUAL LACE BOOT

Thomas M. Adams, Box 682,
Marble Falls, Tex. 78654

Filed Apr. 28, 1975, Ser. No. 572,616

Term of patent 14 years

FIG. 1

FIG. 2

FIG. 3

FIG. 4

Des. 240,972

Page 2 of 2

FIG. 5

FIG. 6

FIG. 7

FIG. 8

FIG. 1 is a right front perspective view of a dual lace boot showing my new design;

FIG. 2 is a front elevational view thereof;

FIG. 3 is a right front perspective view thereof with the upper lace removed;

FIG. 4 is a rear elevational view thereof;

FIG. 5 is a top plan view thereof;

FIG. 6 is a right front perspective view thereof with both laces removed;

FIG. 7 is a left side elevational view thereof; and

FIG. 8 is a bottom plan view thereof.

I claim:

The ornamental design for a dual lace boot, substantially as shown and described.
